(57) **CLAIM**

The ornamental design for a faucet cover, as shown and described.

DESCRIPTION

FIG. 1 is a top, front, left perspective view of a faucet cover showing our new design, depicted in an exemplary environment;

FIG. 2 is a top, front, left perspective view thereof;

FIG. 3 is a top view thereof;

FIG. 4 is a front view thereof;

FIG. 5 is a rear view thereof;

FIG. 6 is a right side view thereof; and,

FIG. 7 is a left side view thereof.

The even length broken lines depicting the remainder of the faucet cover show portions that form no part of the claimed design. The even length broken lines depicting the exemplary environment in FIG. 1 form no part of the claimed design.

1 Claim, 7 Drawing Sheets
